UNITED STATES PATENT OFFICE.

SAMUEL S. HICKOCK, OF METHUEN, MASSACHUSETTS.

IMPROVEMENT IN CASTERS FOR FURNITURE.

Specification forming part of Letters Patent No. 122,016, dated December 19, 1871.

To all whom it may concern:

Be it known that I, SAMUEL S. HICKOCK, of Methuen, in the county of Essex and Commonwealth of Massachusetts, have made an invention of a new and useful Improvement in Wheel-Casters; and do hereby declare the following to be a full, clear, and exact description thereof, due reference being had to the accompanying drawing making part of this specification, and in which—

Figure 1 is an elevation; Fig. 2, a vertical section, and Fig. 3 a horizontal section of a caster embodying my improvements.

This invention relates to a caster which has its supporting-journal pivoted within the wheel-supporting block; and it consists in the combination, with such a caster, of a removable pin passing through the block into the journal to prevent the rotation of the one independently of the other while the caster is being screwed into the leg of the chair or other article of furniture to which it may be applied.

The drawing accompanying this specification represents at A the wheel or roller, and at B the furcated block, in which the roller is pivoted, such parts being similar to those of casters in use at present. In the block B is formed a socket, C, into which a journal or short rod, D, extends, the lower extremity of such rod serving to sustain the weight, or its share of the weight, of the object to which the caster is applied. The rod D extends upward above the block B, and is provided with a ferrule or flange, F, to abut against or inclose the lower end of the leg of the object carrying the caster, the upper portion of the rod

D being formed into a screw, b', to screw into the leg and secure the caster thereto. In this manner is produced a perfect finished joint, which permits the block and wheel to rotate together about the journal with the utmost freedom of motion and with entire absence of noise or shake, as the screw is forced tightly into the wood and the joint between the rod D, and its step or socket is tight and noiseless. In order that the block or wheel shall not drop away from the rod or suspensory D, I cut a peripheral groove, a, in its circumference and extend into this groove a pin, b', which is advanced through the block and so as to intercept such groove; while in order that the rotary motion of the block about the rod may be stopped and the screw rotated with the block, when applying the caster to use, I bore through the block and into the rod a hole, c, into which a pin, d, may be inserted. The screw b' may in some instances be omitted, and the rod D formed with a head and applied directly to the leg of the article of furniture.

I do not claim, broadly, a caster having its supporting-journal pivoted within the wheel-supporting block; but

What I claim as my invention, and desire to secure by Letters Patent, is—

The combination in a caster, such as described, with the rod or journal D and wheel-supporting block B of the removable pin d, substantially as and for the purposes shown and set forth.

SAMUEL S. HICKOCK.
